APPARATUS FOR CREATING FLOW OF DIRT-LADEN FLUID.

1,146,602.

Specification of Letters Patent.

Patented July 13, 1915.

Application filed February 13, 1911. Serial No. 608,258.

To all whom it may concern:

Be it known that I, IRA H. SPENCER, a citizen of the United States, and a resident of Hartford, in the county of Hartford and 5 State of Connecticut, have invented a new and Improved Apparatus for Creating Flow of Dirt-Laden Fluid, of which the following is a specification.

My invention relates generally to the class 10 of devices for producing flow of fluids and especially to devices for creating flow of fluid that is laden to a greater or lesser extent with more or less solid material, and an object of my invention, among others, is to 15 provide a device of this class in which the dirt laden fluid may pass through the device without impairing its action or durability.

One form of device in the use of which the 20 objects sought may be attained is illustrated in the accompanying drawings in which—

Figure 1 is a view in central vertical section through an apparatus embodying my invention. Fig. 2 is a detail view in cross 25 section through the same on plane denoted by dotted line 2, 2 of Fig. 1.

In the accompanying drawings there is 30 illustrated a shell composed of sections 6 preferably circular in form and resting one upon the other, the edges of the sections being provided with interengaging parts to prevent lateral movement of one section upon the other, these resting upon a base section 7, and the whole being secured 35 together as by means of bolts 8 passing through a flange in the base and through a cap 9 located upon the top section. A motor 10 of any improved form of construction is located upon the cap 9 and has a shaft 11 40 vertically disposed and connected with a main shaft 12 vertically arranged within the shell, the lower end of the shaft being located within and supported by a bearing 13 of any suitable form of construction. 45 The top section 14 of the shell is of dish shape having a bottom 15 closing this end of the chamber within the shell. A rib 16 rises from the bottom 15 and within this rib an inlet passage 17 extends horizontally to 50 about the center of the shell where it turns abruptly through the bottom 15 opening into the chamber within the shell, the shaft 12 passing through the rib 16 forming the wall of the passage 17. Each of the sections

have a central opening and within the fan 55 chamber in each of the sections a series of fans 18 are located, these fans being secured to the shaft 12 in any suitable manner, in the form shown a plate 19 secured to a hub 20 fast upon the shaft being employed to 60 receive the fans, each blade having an offset heel 21 projecting into the central opening into the fan chambers.

A diffusing plate 22 is located within each 65 of the compartments in each of the shell sections, these diffusing plates in fact forming one wall of the fan chambers. Diffusing vanes 23 are located at suitable intervals upon the plates 22 and between it and the bottom 24 of the adjoining shell section, 70 being secured in any suitable manner, these diffusing vanes being located tangentially with respect to the disk 19 and extending preferably in a curved line as shown in Fig. 2 of the drawings. The shaft 12 passes 75 through each of the diffusing plates that are suitably packed as shown at 25 against the flow of fluid at this point.

The device herein illustrated and described is intended for use with fluid more 80 or less laden with solid material, and in order to aid the flow of such matter, the shell is vertically arranged so that the material, together with the air currents will pass from the top to the bottom. In order 85 to create the necessary pressure within the shell to effect a proper flow the air or other fluid is thrown outward by the centrifugal action of the fans to the wall of the shell from which point it travels inward to a 90 central opening where it again encounters a fan and the action is repeated, the fluid in each of the succeeding chambers being raised to a greater pressure than that in the next preceding chamber. In order to aid the 95 movement of the solid material with which the fluid is laden, I provide each section 6 with a funnel 26 extending from a point at the inner surface of the shell and near the edge of the diffusing plate therein downward toward the center terminating at the opening 27 in each shell. The inclination of the walls of this funnel may be of any desired degree, but I prefer that it shall be considerable as shown in Fig. 1 of the drawings in order to produce the proper flow of material through the device. This funnel 100 may be a plate located within each section

and joined to the bottom 24, the joined edge forming the wall of the central opening 27.

In the operation of the device a suitable conducting tube being connected to the inlet passage 17 and the motor being in operation, the suction created within the shell formed by the sections 6 causes a flow of air inward at the passage 17. This air laden with solid material to a greater or lesser degree is caught by the heels 21 of the fan blades 18 and is whirled rapidly outward by centrifugal action passing through the spaces between the diffusing vanes 23 that to a great extent stop the whirling circular motion of the air which now travels from the space between the outer edges of the diffusing vanes and the shell toward the central openings 27. The solid matter mixed with the fluid currents is caused to pass along the walls of the funnel 26, the flow of the solid matter being thus aided at this point both by the action of gravity and the force of the air currents, and the entire mass is thus readily moved along the shell to the outlet 28 which may be connected with any suitable source of discharge.

My improved apparatus is found to be especially applicable in devices for moving air currents for the purpose of suction cleaning, as it is found that all of the material picked up by the air currents in the cleaning of public buildings, conveyances and the like may be readily carried through the machine, the construction of which is such as to resist any injury.

While I have shown and described herein one form of apparatus embodying my invention, the invention may be present in structures differing from that herein shown and I do not, therefore, limit myself to the embodiment of the invention in an apparatus as exactly herein shown and described.

I claim:

1. In an apparatus of the class described, a shell, a shaft vertically mounted in the shell, means for rotating the shaft, a number of fan blades secured to said shaft, a chamber inclosing each of the sets of blades by walls extending along the side edges thereof whereby material is forced off at the ends of the blades, a funnel shaped surface disposed to receive flow delivered from said blades and to permit the action of gravity as an assistance in conducting said flow downward to the opening at the center of the shell about the shaft, and the wall of the fan chamber constituting the top of a funnel shaped chamber unobstructed as to its top and bottom walls.

2. In an apparatus of the class described, a shell, a shaft vertically mounted in the shell, means for rotating the shaft, a disk secured to the shaft, a number of fan blades, each blade being secured along one edge to said disk and the other traveling in close

relation with the wall of the fan chamber, and a funnel shaped surface disposed to receive flow delivered from said blades, said funnel shaped surface extending downwardly from the point of delivery of matter thereto to the center of the shell, said surface being arranged to permit the action of gravity as an assistance to said flow to the opening at the center of the shell, the top wall of said funnel shaped chamber being flat and constituting one of the parallel walls of the fan chamber.

3. In an apparatus of the class described a shell composed of sections, each section having a funnel shaped wall flaring upwardly and outwardly and with a diaphragm extending at right angles to the axis of the section with a contracted opening formed at the junction of said diaphragm and said funnel shaped wall, a diaphragm extending across the mouth of the chamber formed by said funnel shaped wall, fans located between said diaphragms, a shaft extending through the section, and means about the shaft for preventing flow of air at that point.

4. In an apparatus of the class described, a shell, a shaft vertically mounted in the shell, means for rotating the shaft, fan blades secured to said shaft in sets, a funnel located underneath each of the sets of fan blades and arranged to permit the action of gravity as an assistance to flow to the contracted opening of the funnel, and a diffusing plate forming one wall of a fan chamber and partially closing the enlarged end of said funnel, said diffusing plate being smaller in size than the mouth of the funnel whereby a passage is left into the funnel around the edge of the diffusing plate.

5. In an apparatus of the class described, a shell, a shaft vertically mounted in the shell, means for rotating the shaft, a diaphragm having an opening at its center and forming one wall of a fan chamber with an opening at its center, a second diaphragm forming the opposite wall of the fan chamber, fan blades secured to the shaft within the fan chamber and a funnel shaped surface disposed to receive flow delivered from said blades and to permit the action of gravity as an assistance to said flow downwardly within said shell.

6. In an apparatus of the class described, a shell, a shaft vertically mounted in the shell, means for rotating the shaft, a number of fan blades secured to said shaft, said blades being arranged in sets, a funnel located underneath each set of blades with its small end opening downwardly, said funnel being arranged to permit the action of gravity as an assistance to flow to the outlet from the funnel, a diffusing plate partially closing the mouth of the funnel and smaller in size than said mouth whereby a passage is

left about the edge of the diffusing plate into the mouth of the funnel, said diffusing plate forming one wall of a chamber in which a set of fan blades is located, the periphery of the circle defined by the outer

located in the space between the ends of the fan blades and the outer edge of the diffusing plate.

IRA H. SPENCER.
